STEERING WHEEL

Rodger E. Geller, Dayton, Ohio, assignor to General Motors Corporation, Detroit, Mich., a corporation of Delaware

Original design applications Oct. 23, 1963, Ser. No. 77,115, now Design Patent No. 200,636, dated Mar. 23, 1965, and Oct. 1, 1964, Ser. No. 82,213. Divided and this application Jan. 26, 1965, Ser. No. 83,886

Term of patent 7 years

(Cl. D14—30)

Fig. 1

Fig. 2

FIGURE 1 is a plan view of a steering wheel showing my new design.

FIGURE 2 is an elevational view taken along line 2—2 in FIGURE 1 and on a reduced scale.

This is a division of parent applications Serial Nos. D-77,115 filed October 23, 1963 now Patent No. D-200,636 granted March 23, 1965 and D-82,213 filed October 1, 1964, respectively.

The dominant features of my design reside in the portions shown in full lines.

I claim:

The ornamental design for a steering wheel, as shown and described.
